UNITED STATES PATENT OFFICE.

GIDEON A. CLOSE, OF BRIDGEPORT, CONNECTICUT.

DEVICE FOR CLAMPING PATTERNS ON GOODS.

SPECIFICATION forming part of Letters Patent No. 282,410, dated November 13, 1883.

Application filed June 22, 1883. (No model.)

To all whom it may concern:

Be it known that I, GIDEON A. CLOSE, a citizen of the United States, residing at Bridgeport, in the county of Fairfield and State of Connecticut, have invented certain new and useful Improvements in Devices for Clamping Patterns on Goods; and I do hereby declare the following to be a full, clear, and exact description of the invention, such as will enable others skilled in the art to which it appertains to make and use the same.

My invention relates to certain novel and useful improvements in devices for clamping patterns on goods for the purpose of holding the latter during the process of cutting, and has for its object to provide such a device as shall be simple in its construction and ready in adjustment, while at the same time its action shall be positive; and with these ends in view my invention consists in the details of construction and combination of elements hereinafter fully explained in detail, and then specifically designated by the claims.

In order that those skilled in the art to which my invention appertains may understand more fully the construction and operation of my improvement, I will proceed to describe the same in detail, referring by letter to the accompanying drawings, forming a part of this specification, in which—

Figure 1 is a side elevation of my improvement in operative position; Fig. 2, a vertical section of what will be hereinafter referred to as "the block," and showing the swivel-connection between the latter and the standard; Fig. 3, a similar view of the clamping-bar, showing a similar connection with the presser-foot; Fig. 4, a vertical section with the clamping-bar broken away, and showing the arrangement of the lock and jam nuts around the said bar; Fig. 5, a front elevation, showing the manner of attaching the clamp to the collar-nut and the guide-arm; and Fig. 6, a plan view, showing the presser-foot clamped down on a pattern.

Similar letters denote like parts in the several figures of the drawings.

A is the standard, which is held in an upright position within sockets B by means of set-screws C, passed through said sockets, which latter are bolted to the cutting block or table. At the upper portion of this stand-

ard is a block, D, which is swiveled to said standard in any ordinary way, as plainly shown at Fig. 2. E is a supporting-arm, 55 which is passed through a longitudinal opening in the block (see Fig. 2) in such a manner as to slide freely.

F is the clamping-bar, extending through the supporting-arm, so as to have a free vertical play therein. G is an elbow-lever pivoted to the supporting-arm, and with its elbow-projections H toggle-jointed with the rods I, as seen at Figs. 1 and 5. The rods I are pivoted at their lower extremities to a collar, J, 65 on the bar F, for the purpose presently explained. This collar is supported by nuts K L, traveling on the bar F, the latter nut acting as a lock to keep the former from working down, all of which will be readily understood 70 by reference to Figs. 1 and 4.

M is the presser-foot, swiveled in any ordinary manner (see Fig. 3) to the clamping-bar.

N is a collar on the upper portion of the bar and resting upon the supporting-arm.

O is a coil-spring confined on said bar between the collar N and a cross-pin, P.

The operation of my improvement is as follows: The cloth or other fabric which is to be cut is placed on the cutting block or table in 80 as many layers or thicknesses as desired. The pattern is then placed over and upon the cloth, &c., and the supporting-arm pulled out, pushed in, or swung around, as the case may be, in order to bring the clamping-bar in position, so that the presser-foot will be in the proper position above the pattern. The lever G is now depressed, and the elbows H and rods I will straighten out, thereby forcing down the clamping-bar, so that the foot M 90 presses the pattern firmly against the goods, and the latter can now be cut around the pattern without any danger of slipping. The clamping-bar is bowed, as shown at Fig. 1, because a vertical bar would interfere with 95 the operator in cutting; also, said bowed bar may be readily swung around while under pressure to one side when the operator is cutting, for the purpose of convenience. After the operation of cutting, the lever is raised 100 and the coil-spring returns the bar to its normal position. Should a greater throw of the bar be desired, this may be accomplished by setting up the nuts K L, which will cause the

elbows H and rods I to form a more acute angle in their normal position.

The standard A may be raised or lowered by simply loosening the screws C and sliding it within the sockets B, and the normal vertical position of the clamping-bar adjusted thereby. This latter adjustment is especially desirable in order to bring the presser-foot to a certain plane above the goods, where the 10 clamping mechanism can operate readily, and this plane depends, of course, on the thickness of the goods to be cut. In cutting around large patterns the presser-foot may be readily shifted to any part of the pattern, if desired, 15 in order to get more pressure at the particular point; also, my improved device may be used with great facility in cutting around extremely long patterns, since the supporting-arm may be turned in any direction and 20 moved throughout its whole length and the presser-foot shifted accordingly.

Prior to my invention it has been common to nail the patterns down on the goods through the cutting-block; but this not only consumed 25 considerable time both in driving in and extracting the nails, but the goods themselves were necessarily mutilated thereby, and very often spoiled entirely. My invention overcomes these difficulties and does the work in 30 less time and without marring the goods in the least.

Having thus described my invention, what I claim as new, and desire to secure by Letters Patent, is—

35 1. In a clamping device, as described, the clamping-bar swiveled to the presser-foot and bowed at its lower portion, and operated in a vertical plane by a toggle-jointed lever, substantially as set forth.

2. The vertically-adjustable standard provided at its upper extremity with swiveled block, in combination with the supporting-arm arranged to slide horizontally within said block, and clamping-bar having attached at its lower extremity a swiveled presser-foot, 40 and operated in a vertical plane by a toggle-jointed lever, substantially as described.

3. In a device for clamping patterns onto goods, a clamping-bar operated in a vertical plane by a toggle-jointed lever, and having 50 attached at its lower extremity a swiveled presser-foot, in combination with an adjustable swiveled supporting-arm, substantially as set forth.

4. In a device for clamping patterns onto 55 goods, an adjustable supporting-arm, in combination with a clamp-bar operated in a vertical plane by a toggle-jointed lever, substantially as described.

5. In a device for clamping patterns on 60 goods, a presser-foot swiveled to a clamp-bar, in combination with an operating-lever and a swiveled supporting-arm, as set forth.

6. The clamp-bar, bowed as described, near its central portion, in combination with a swiveled presser-foot, substantially as described. 65

7. The combination of the clamp-bar F, presser-foot M, spring O, collar N, supporting-arm E, collar J, nuts K L, toggle-jointed lever, swiveled block D, and standard A, substantially as set forth. 70

In testimony whereof I affix my signature in presence of two witnesses.

GIDEON A. CLOSE.
